M. THEIMER,
BONE HOLDING DEVICE,
APPLICATION FILED DEC. 3, 1919.

1,342,515.

Patented June 8, 1920.

Inventor
Max Theimer

By his Attorney

Albert Berman

UNITED STATES PATENT OFFICE.

MAX THEIMER, OF ELIZABETH, NEW JERSEY.

BONE-HOLDING DEVICE.

1,342,515.

Specification of Letters Patent. Patented June 8, 1920.

Application filed December 3, 1919. Serial No. 342,298.

To all whom it may concern:

Be it known that I, MAX THEIMER, a citizen of the United States, residing at Elizabeth, in the county of Union and State of New Jersey, have invented new and useful Improvements in Bone-Holding Devices.

My invention consists of a device suitably constructed to assist in rigidly holding a bone during the operation of sawing said bone. Hitherto such devices have been of a construction in general resembling a bench vise. But owing to the inherent irregularities in the shapes of bones, the comparatively large bearing areas of the jaws of such vises do not properly grip the bones. In addition to this, said vises are bulky, and being rigidly fixed to the butcher's block or other table are in his way when performing operations other than bone sawing. An important feature of my device is the use of a comparatively thin plate suitably notched to receive the bone, affording a knife edge grip, which is not weakened by irregularities in the shape of the bone. Furthermore the sides of the notch are serrated, being furnished with sharp teeth in general, having their axes pointing downward. This greatly assists in holding down the bone in the notch and preventing its rotation, it being understood that one end of the bone is held by the operator, while the other end rests in the notch. A further feature of my invention is that the notched plate is suitably mounted to permit of its being easily moved into inoperative position, out of the way of the butcher when its use is not required. Owing to its flat shape and small size, my bone holding device is very compact in its inoperative position, affording a minimum of interference with the movements of an operator about the table. The other features of this device will be made evident from the detailed description.

Reference is to be had to the following drawings illustrating my device, in which—

Figure 1 is a front elevation of my preferred form, with the device in operative position.

Fig. 2 is a section along the line 2—2 of Fig. 1.

Fig. 3 is a front elevation of my preferred form in its inoperative position.

Fig. 4 is an elevation of the notched plate.

Fig. 5 is a perspective of the bracket support.

Figs. 6 and 7 are views respectively of operative and inoperative positions of an alternative form of my invention in which the notched plate is adapted to slide into inoperative position.

Figs. 8 and 9 are views respectively of operative and inoperative positions of an alternative form of my invention in which the notched plate is adapted to swing sidewise into inoperative position.

Figs. 10 and 11 are views respectively of operative and inoperative positions of an alternative form of my invention in which the notched plate is detachable.

Referring now to Figs. 1, 2, 3, 4 and 5, the bracket 1 is provided with holes through which screws 2 can be passed for fastening the bracket to the meat block. The upper portion of bracket 1 is bent over to form the guides 3, and the lower portion is bent over to form the guides 4. The upper and lower portions of guides 4 are bent to substantially horizontal planes as shown in Fig. 2 in order to limit the motion of plate 5. The curved V shaped notch 9 of plate 5 is provided preferably with acute-angled teeth 10. The sides of plate 5 are provided with indentations with outer portions 6 which are adapted to fit over the outside of guides 3 (Figs. 1 and 3) and inner curved portions 7 which fit within guides 3 when plate 5 is in its operative position. The rounding of portion 7 facilitates its entrance into the guides 3. Integral with the lower end of plate 5 (Fig. 4) are lugs 8, which are adapted to play within the guides 4.

In operation, the plate 5 is in the erect position shown in Fig. 1. The butcher can now insert the bone into the curve V shaped notch 9. It is preferable to insert the heavier end of the bone into the notch holding the lighter end in one hand and wielding the bone-saw with the other. The sides of the V notch are made curved to more nearly conform to the shape of the average bone.

When the butcher is through using the device, in order to move plate 5 into its inoperative position, he first lifts it into the dotted position shown in Fig. 1 in order to clear the portions 6 and 7 of the guides 3. Then he swings plate 5 outwardly pivoting upon the lugs 8, and releases it. Plate 5 assumes the position shown in Fig. 3 hanging from its lugs 8 in the bottom of the guides 4.

Several alternative forms of my device

can be made following the same general principles as outlined in connection with Figs. 1 to 5 inclusive.

Referring now to Figs. 6 and 7 the notched plate 11 is held in a support with guides 12. Fixed to the outside of the guides are spring latches 13 adapted normally to prevent the plate 11 from sliding downward through the guides 12. At the top of plate 11 are lugs 14 which limit the downward motion of said plate when released by the pulling sidewise of latches 13.

Figs. 8 and 9 show a modification in which the notched plate 15 is adapted to swing about a pivot 16. The plate 15 is maintained in its operative position by means of latch 17 which engages with stop 18. Upon lifting latch 17 up out of engagement with stop 18, plate 15 can be swung down into its inoperative position as shown in Fig. 9.

Figs. 10 and 11 show a detachable type in which the notched plate 19 is supported in guides 20. Plate 19 can be moved into inoperative position by lifting it out of the guides 20 and letting it fall into inoperative position where it hangs suspended by chain 21.

Having thus fully described my invention, I claim as new, and wish to secure by Letters Patent:—

1. In a bone holding device the combination of a thin plate having a toothed notch and a support for said plate, said support and said plate being suitably constructed to permit the lowering of said plate into inoperative position.

2. In a bone holding device, the combination of a plate having a curved V shaped notch with teeth in it and a support for said plate, said support and said plate being suitably constructed to permit the lowering of said plate into inoperative position.

3. In a bone holding device, the combination of a plate having a bone holding notch in it, the sides of said notch having a plurality of teeth, said teeth having their axes pointing downward, and a support for said plate, said support and said plate being suitably constructed to permit the lowering of said plate into inoperative position.

4. In a bone holding device, the combination of a plate having a bone holding notch in it and projecting lugs, and a support for said plate having guides suitably constructed to engage said lugs, said guides being constructed to constrain said lugs to have a limited up and down motion.

5. In a bone holding device, the combination of a plate having a notch in it and projecting lugs and a support having guides

adapted to engage said lugs, said guides and said lugs being suitably constructed to permit the rotation of the lugs within said guides.

6. In a bone holding device, the combination of a plate having a toothed notch in it and a support having guides adapted to have a part of said plate slide within them.

7. In a bone holding device, the combination of a plate having a notch in it, said plate also having indentations, and a support for said plate having guides suitably constructed to permit portions of the plate at the indentations to slide within them and other portions to overhang them.

8. In a bone holding device, the combination of a plate having a notch in it, said plate also having indentations and lugs, and a support for said plate having guides suitably constructed to permit portions of the plate at the indentations to slide within them and other guides suitably constructed to engage said lugs, said lugs and latter guides being constructed to permit a limited up and down motion and a swinging motion of said plate.

9. In a bone holding device, the combination of a plate having a toothed notch in it, and a support for said plate, said plate and said support being operatively connected and suitably constructed to enable the plate to be swung into its inoperative position without detaching it from said support.

10. In a bone holding device, the combination of a plate having a substantially V shaped bone holding notch in it, and a support for said plate, said support and said plate being suitably constructed to permit the lowering of said plate into inoperative position.

11. A meat-holding device comprising an attaching plate adapted to be secured to a meat-block or the like, a meat gripping member, means for mounting said meat gripping member on the attaching plate to permit it to be moved to an operative position above the surface of a meat-block or downwardly out of the way, and means for locking the meat-gripping member in its elevated operative position.

12. A meat-holding device comprising an attaching plate adapted to be secured to a meat-block or the like, a meat gripping member, means for pivotally mounting said meat gripping member on the attaching plate to permit it to be swung to an operative position above the surface of a meat-block or downwardly out of the way, and means for locking the meat-gripping member in its elevated operative position.

MAX THEIMER.
